MACHINE FOR APPLYING COVERINGS TO
POCKETBOOK FRAMES

Everett D. Sirois, Newburyport, Mass.

Application November 8, 1937, Serial No. 173,540

4 Claims. (Cl. 154—41)

This invention relates to a machine for efficiently, quickly and completely applying coverings to pocketbook frames and has for the primary object the provision of a device of this 5 character which will eliminate the present unsatisfactory and expensive practice of applying, fitting and securing coverings on frames by hand.

Another object of this invention is the provision of a machine of the above stated character 10 which is so constructed that a pocketbook frame having a covering partly applied thereto by adhesive or held thereon by hand, may be easily and quickly placed on the machine whereby during the operation of the latter, the covering will be 15 tightly stretched onto the frame free of wrinkles or creases and forced tightly into the channels of the frame so that said covering will remain firmly and smoothly applied ready to be permanently secured on the frame by clinching the latter after 20 the securing of the body of the pocketbook onto the frame.

With these and other objects in view, this invention consists in certain novel features of construction, combination and arrangement of parts 25 to be hereinafter more fully described and claimed.

For a complete understanding of my invention, reference is to be had to the following description and accompanying drawings, in which

30 Figure 1 is a front elevation illustrating a machine for applying coverings to pocketbook frames and is constructed in accordance with my invention.

Figure 2 is a rear elevation illustrating the 35 same.

Figure 3 is a sectional view taken on the line 3—3 of Figure 1.

Figure 4 is a sectional view taken on the line 4—4 of Figure 2.

40 Figure 5 is a sectional view taken on the line 5—5 of Figure 1.

Figure 6 is a fragmentary transverse sectional view showing the initial application of a pocketbook frame on the machine.

45 Figure 7 is a detail sectional view taken on the line 7—7 of Figure 1.

Figure 8 is a front elevation showing a pocketbook frame in a fully applied position on the machine having been moved into said position

50 through one stage of operation of the machine.

Figure 9 is a fragmentary plan view showing one of the cams and the jaw operating arms therefor, the cam occupying a position when the machine has substantially completed its first 55 stage of operation.

Figure 10 is a plan view showing another cam for the control of cover wedging elements of the machine which act to force the covering into the channel of the frame, said cam being shown as occupying the position during the first stage 5 of operation of the machine.

Figure 11 is a fragmentary transverse sectional view showing the pocketbook frame applying element in the position of fully applying the pocketbook frame on the machine. 10

Figure 12 is a fragmentary transverse sectional view showing the relation of the pocketbook frame to one of the jaws of the machine prior to the second stage of operation of the machine.

Figure 13 is a fragmentary front elevation 15 showing the machine acting on the covering and pocketbook frame to tightly stretch the covering on the frame.

Figure 14 is a plan view showing the cam which operates the cover wedging elements of the machine in a position after the machine has acted to fully apply the frame on said machine. 20

Figure 15 is a fragmentary transverse sectional view taken on the line 15—15 of Figure 13.

Figure 16 is a detail sectional view taken on 25 the line 16—16 of Figure 13.

Figure 17 is a plan view showing the cam which controls the cover wedging elements of the machine in a position after the initial wedging of the covering in the channel of the frame by the 30 cover wedging elements of said machine.

Figure 18 is a fragmentary rear elevation, partly in section, showing the third or final stage of operation of the machine wherein the covering has been forced into the channel of the pocket- 35 book frame.

Figure 19 is a fragmentary sectional view taken on the line 19—19 of Figure 18.

Figure 20 is a fragmentary sectional view taken on the line 20—20 of Figure 18. 40

Figure 21 is a fragmentary plan view partly in section showing the position of the cam which operates the jaws during the third stage of operation of the machine.

Figure 22 is a plan view showing the cam which 45 controls the cover wedging elements of the machine in a position after said wedging elements have acted initially to wedge the covering in the channel of the frame.

Referring in detail to the drawings, the number 1 indicates a base supporting a vertically arranged plate-like support 2 and journals 3 for a shaft 4, the latter being either manually or power driven. The shaft 4 is disposed horizontally and extends through an opening in the sup- 50

55

port 2 and has secured thereon cams 5, 6 and 7. The cams 5 and 6 may be of integral construction and are located on one side of the support 2 while the cam 7 is located on the other or opposite side of the support from the cams 5 and 6. The cam 5 is preferably of the track type, as clearly shown in Figures 1, 8 and 21, and is engaged by a roller 8 carried by a slide 9 forming a part of the mechanism for fully applying a pocketbook frame 10 on the machine. The slide 9 operates in guides 11 secured on one side face of the support 2. The slide 9 includes pivotally connected sections A and B. The section A during one position of the cam 5 moves out of the guides 11 so as to have a pivotal movement and has secured thereto a pocketbook frame engaging arm 12 adapted to engage with one of the fastening elements 13 of the pocketbook frame and which is conventional construction of the latter. The arm 12 when in engagement with the fastener 13 lies between the latter and the pocketbook frame. A spring 14 is connected to the sections A and B of the slide 9 so that the section A when out of the guides 11 will assume a position angularly to the section B for positioning the arm 12 away from the pocketbook frame or the latch element 13 thereof, as shown in Figure 5.

Mounted on the upper end of the support 2 is a pocketbook frame receiving device C consisting of yieldably connected jaw plates 16 the upper edges of which curve outwardly and away from each other. The jaw plates 16 may move apart on the forcing of a pocketbook frame therebetween and the opposing faces of said jaw plates have shoulders 18. Headed pins 19 extend through the jaw plates 16 and interposed between the heads thereof and said jaw plates are springs 20 acting to urge the jaw plates towards each other. In one of said jaw plates is a slot 21 to permit the arm 12 to pass therethrough to engage the fastening element 13 of the pocketbook frame and to move downwardly. The headed pins 19 also extend through openings of the support 2 whereby the jaw plates are movably connected with the latter.

The device C also includes pivotally mounted jaws D each of substantially L shape and including spaced jaw plates 22 yieldably connected to each other by headed bolts 23 on which coil springs 24 are mounted. The coil springs 24 act to urge the jaw plates 22 in the direction of each other being limited in the movement in the direction of each other by the pivotal connection between said jaw plates 22 and the jaw plates 16 of the device C, the pivotal connection being indicated by the character 25. The jaws D are arranged at opposite ends of the device C and may assume outward and downward positions, as shown in Figure 1, or assume positions in an upward direction, as shown in Figures 13 and 18. Normally the jaw plates 22 are spaced away from each other approximately the same distance as the jaw plates 16 and are forced apart only by their engagement with the pocketbook frame which also applies to the jaw plates 16. The jaws D have arms 26 secured thereto by the bolts 23 and are in turn pivotally and slidably connected to bell crank levers 27 pivotally mounted on the support 2 and which contact the cam 6 being forced into engagement with the latter by a coil spring 28 connecting said bell crank levers adjacent their pivotal connections with the arms 26. The cam 6 acts to move the jaws into their different positions. The opposing faces of the

jaw plates 22 of the jaws have formed thereon beveled shoulders 29.

A cross head 30 is slidably mounted on the support 2 for vertical movement and includes a roller 31 which rides the cam 7 under the influence of coil springs 32 secured to the support and to the cross head. Upwardly extending levers 33 are pivotally connected to the cross head and supported in guides 34 on the support 2 and terminate a distance above the device C and have secured to their upper ends cover wedging elements or plates 35 the adjacent edges of which are formed on an angle providing pointed portions 36. The levers 33 are connected by a coil spring 37 acting to urge said levers in the direction of each other and the guides 34 cause said levers to move towards each other as the cross head 30 moves upwardly to bring the cover wedging elements or plates into overlapping relation and in a position well above the device C. However, as the cross head moves downwardly the guides 34 act to move the levers apart bringing about a separating movement of the cover wedging plates from each other as they move downwardly in the direction of the device C. The cam 7 which operates the cross head includes high portions E, F and G having between said high portions low portions either one of which will permit a full downward movement of the cross head. The high portion E is considerably longer than the high portions F and G. The guides 34 include rollers 38 which levers 36 engage under the influence of the spring 37.

Usually pocketbook frames are composed of companion hingedly connected sections, each section of channeled formation and of substantially U shape, as shown in the drawings. The machine described is especially adapted to apply covering material 40 on each section by acting on the sections one at a time. However, this machine will successfully apply covering to pocketbook frames other than the type shown providing that the frame is of channeled construction and perhaps it may be necessary to modify the shapes of the jaws from that shown to match with the particular shape of pocketbook frame that is to be covered. Usually the sections of the pocketbook frame have secured thereto the fastening elements indicated by the character 13, however, pocketbook frames minus such fastening elements may have covering applied thereto by this machine providing that the operator manually applies the pocketbook frame in a full applied position in the machine and in this case the arm 12 as well as the slide 9 will be omitted or rendered inoperative in any well known manner. The covering for the pocketbook frame is cut or otherwise formed into strip formation of a length sufficient to extend the full length of one of the sections of the pocketbook frame and of a width to completely cover the section of the frame with the free edges projecting well beyond the frame and at the channeled side thereof. The covering thus formed is partly applied to a section of the pocketbook frame manually either being secured thereto by adhesive applied to the covering or the frame section or held manually until placed on the machine.

In operation, the various parts of the machine are positioned, as shown in Figure 1, by rotating the shaft 4 by the operator. The pocketbook frame is then taken by the operator and a strip of covering is applied to one section of the frame, as shown in Figure 1, and said section is brought into engagement with the jaw plates 16 of the

device C with the fastening element of said section extending between the jaw plates 16. At this time the covering material is only loosely applied to the pocketbook frame and may have 5 loose or free portions not adhered to the frame or held thereon manually. The operator on the initial operation of the machine rotates the shaft or permits rotation thereof by a power means if the latter is employed. During the 10 initial operation of the machine the arm 12 moves into engagement with the fastening element of the frame and downwardly, drawing the frame and covering well between the jaw plates 16 of the device C. This operation of the arm 12 is caused by the cam 5. At this time the jaws 15 D are spread by the high portion of the cam 6. The frame moving between the jaw plates 16 smoothly applies a portion of the covering on a portion of the frame and on further rotation 20 of the shaft the cam 6 acts to move the jaws 22 onto the frame applying to the covering a stretching and smoothing action so that the covering will be smoothly applied to the frame from one end of the covering to the other, the free 25 edges projecting well beyond the channeled face of the frame. The jaws remain in engagement with the covering while the cam 7 acts to permit the springs 32 to move the cross head downwardly, bringing the plate-like elements 35 downwardly and outwardly. The plate-like elements 30 35 moving downwardly and outwardly force the free edges of the covering tightly into the channel of the frame, as shown in Figures 19 and 20. The roller 31 of the cross head is moved from the high face E to the low face between the high 35 faces E and G to bring about the forcing of the cover into the channel of the frame by the plate-like elements 35. The roller 31 passes onto the high portion G which brings about upward 40 and inward movement of the plate-like elements 35 to become disengaged from the covering and the frame. As the roller 31 passes from the high portion G to the low portion between said high portion G and the high portion F the plate-like 45 elements 35 are again forced into the channeled portion of the frame further wedging the covering therein. The roller 31 then passes onto the high portion F of the cam 7 again raising the plate-like elements 35 from the frame and covering. The roller 31 passes from the high portion 50 F to the low portion between said high portion F and the high portion E of the cam 7 again permitting the springs 32 to move the plate-like elements 35 into the channel of the frame to further wedge the material into the channel 55 of the frame. During these stages of operation the jaws remain in engagement with the covering and frame and the arm 12 remains in its lowermost position maintaining the frame tightly between the plate-like jaws 16 of the holding device C. As the roller 31 passes onto the high portion E from the low portion previously engaged by the cam 7, the plate-like elements 35 are raised away from the frame and towards 60 each other and at this time the cam 5 raises the slide 9 and the spring 14 acts to position the arm 12 free of the latch element of the pocketbook frame, also the cam 6 acts to move the jaws 22 away from the pocketbook frame. The 65 operator then may lift the pocketbook frame off of the machine with the covering smoothly and tightly applied and wedged into the channel of the frame ready to have the usual body of the pocketbook attached thereto by insertion into 70 the channel of the frame and the clinching of 75

the frame thereon by any well known method. As the pocketbook frame is lifted from the machine by the operator the covering is efficiently applied thereto free of wrinkles.

Should it be found that one operation of the 5 plate-like elements 35 on the cover and frame for the purpose of wedging the covering in the channel of the frame to be sufficient the portions F and G of the cam 7 may be omitted, these portions only being employed so that a 10 triple action of the plate-like elements 35 will be had on the covering and the pocketbook frame.

The pocketbook frame when moved fully between the jaw plates 16 of the holding device 15 C assumes a position below the shoulders 18 so that said shoulders move over the channeled face of the frame and thereby securely support the frame to be acted on by the jaws 22 and the plate-like elements 35. The tapering 20 faces 29 of the jaws act to guide the covering over the channeled face of the frame as said jaws move into cover applying position. When the jaws move into inoperative or non-cover 25 applying position and as they move relative to the frame they are spread apart and move therewith the plate-like jaw 16 of the holding device C so as to free the frame from the holding device C.

Pocketbook frames are covered with various 30 kinds of materials. However, a large percentage of the frames are covered with material having a cloth backing. The present practice is to apply the covering by hand and the covering must be cut on the bias causing a large waste 35 of material, also the material is cut by hand making a very slow and expensive procedure. With the use of the present machine as described in this application the material may be cut in the direction of the grain or weave and only on 40 the bias if desired. Cutting the material in the direction of the weave reduces to a minimum the waste of materials. Rolls of the material may be cut by machine eliminating hand cutting and may be accomplished quicker and cheaper. 45 In some instances the covering may be treated on one face with adhesive. In other instances, the initial applying of the covering at points on the frame manually may be accomplished by applying adhesive onto the frame at said points 50 and bringing the covering in contact therewith. In other instances, when it is not desired to apply adhesive the covering may be held by the operator at the selected points on the frame when the latter is applied on the machine. 55

What is claimed is:

1. A machine of the character described comprising a support, a holding means carried by said support including yieldably connected plate-like jaws adapted to have a pocketbook frame with 60 a partially applied covering engaged therewith, an arm to engage the pocketbook frame and draw said pocketbook frame and covering between the plate-like jaws, a guide mounted on said support, a slide movable in said guide and having a hinged 65 section to which said arm is fixed, said section operable to positions in and out of said guide for actuating said arm, a spring connected to said slide and said hinged section biasing said section out of alignment with said guide for 70 maintaining said arm out of engagement with said pocketbook frame when said hinged section is moved out of said guide, said section being forced into alignment with said guide as it is moved therein, a cam mechanism carried by said 75

- support and connected to said slide for operating said hinged section into and out of said guide whereby to effect engagement and disengagement of said arm with said pocketbook frame respectively, jaws pivotally connected to said first means and including yieldably connected jaw plates, linkage connected to said jaws for the actuation of the latter to bring about stretching of the covering on the frame and positioning of edges of the covering adjacent a channel in the frame, said linkage being pivoted to the support for the operation of the jaws, a cam mechanism for operating said linkage, means for forcing the edges of the covering into the channel of the frame, and a cam mechanism for operating said last-named means.
2. A machine of the character described comprising a support, a holding means carried by said support including yieldably connected plate-like jaws adapted to have a pocketbook frame with a partially applied covering engaged therewith, an arm to engage the pocketbook frame and draw said pocketbook frame and covering between the plate-like jaws, a guide mounted on said support, a slide movable in said guide and having a hinged section to which said arm is fixed, said section operable to positions in and out of said guide for actuating said arm, a spring connected to said slide and said hinged section biasing said section out of alignment with said guide for maintaining said arm out of engagement with said pocketbook frame when said hinged section is moved out of said guide, said section being forced into alignment with said guide as it is moved therein, a cam mechanism carried by said

support and connected to said slide for operating said hinged section into and out of said guide whereby to effect engagement and disengagement of said arm with said pocketbook frame respectively, jaws pivotally connected to said first means and including yieldably connected jaw plates, linkage connected to said jaws for the actuation of the latter to bring about stretching of the covering on the frame and positioning of edges of the covering adjacent a channel in the frame, said linkage being pivoted to the support for the operation of the jaws, a cam mechanism for operating said linkage, means for forcing the edges of the covering into the channel of the frame and including slidably mounted levers on said support each having secured thereto a plate-like element movable towards and from each other and having downward and upward movements, a cross head slidably on the support and connected to said levers, spring means connected to said cross head and to the support, and a cam mechanism engageable with the cross head.

3. The elements of claim 2 as set forth and defined therein including, a power shaft journaled on the support and having the cam mechanisms secured thereto.

4. The elements of claim 2 as set forth and defined therein including, a power shaft journaled on the support and having the cam mechanisms secured thereto, and shoulders formed on opposing faces of the jaw plates of said first means, said plates of the jaws having opposed beveled faces.
